UNITED STATES PATENT OFFICE.

JESSE ALEXANDER, OF BROOKLYN, NEW YORK, ASSIGNOR, BY MESNE ASSIGNMENTS, TO LEE ALEXANDER, KITTIE ALEXANDER, JR., JESSE ALEXANDER, JR., AND TYVE ALEXANDER.

TYPE-WRITER PLATEN-SHIFTING MECHANISM.

No. 833,284.

Specification of Letters Patent.

Patented Oct. 16, 1906.

Original application filed June 2, 1902, Serial No. 109,925. Divided and this application filed March 9, 1903. Serial No. 146,898.

To all whom it may concern:

Be it known that I, JESSE ALEXANDER, a citizen of the United States, residing at Brooklyn, in the county of Kings, State of New York, have invented certain new and useful Improvements in Type-Writer Platen-Shifting Mechanism, of which the following is a full, clear, and exact description.

My invention relates to improvements in type-writers, and particularly to the mechanism for effecting the shifting of the platen in that class of machines known as the "shift" type, other details of construction of which are more fully set forth in the application filed by me June 2, 1902, Serial No. 109,925, from which this is a divisional application.

The object of this invention is to construct key - operated mechanism for shifting the platen from the lower to the upper case position in a simple and easy manner and which will be durable.

The object is also to provide a means for automatically locking the carriage or platen in the upper-case position when raised by means of one key-bar and of releasing it by the operation of another key-bar.

It will be found to consist in the improvements more fully set forth in the accompanying drawings and the specification hereinafter.

Figure 1 is a cross-section and side elevation of the parts of a type-writer embodying the improvements of my invention, showing the platen raised to the upper-case position. Fig. 2 is a side elevation, slightly enlarged, of the shifting mechanism. Fig. 3 is a plan view of a fragment of the frame of the machine with the carriage in place, the platen being omitted. Fig. 4 is a side view of the same with the platen in place and showing a type-bar dotted in the printing position.

The reference-figures are substantially the same as those used in the original application.

2 is a revoluble platen carried by the side plates 7.

22 is a side frame which constitutes a part of the carriage. These are pivotally connected at the rear.

221 is a bar which connects the two side frames 22. 23 is a guide-sleeve secured to

this bar 221, which is adapted to slide on the track-bar 24.

222 is a front track carried by the side frames 22, which has bearings in a stationary support 224, carried by the frame of the machine.

131 is an auxiliary rail carried by the side plates 7 and with which the platen-shifting roller 91 co-operates.

The carriage is, as usual in all machines of this character, adapted to be moved from side to side of the machine and is governed by a suitable feed mechanism—as, for instance, a longitudinal rack 26, the gear 27 in engagement therewith, a shaft 28 carrying this gear 27, and a ratchet 29, a dog 30 and the universal mechanism, bar 31, arm 32, shaft 33, and lever 34, link 35, and spring 36. The tension of the spring, and consequently the touch of the machine, may be adjusted by means of the screw 361 and fixed by the set-nut 362 against the frame 363.

81 is one of the intermediate levers of the key and type-bar mechanism, which co-operates with the type-bar 82.

The parts of the machine are shown in what is termed the "upper-case" position.

For shifting the platen or raising it from the lower to the upper case position the key-bars 84 and 85 are provided. These are pivoted at the rear of the machine on the left and right hand sides, respectively.

In Fig. 1 the section of the machine is taken so that the mechanism connected with the left-hand key-bar 84 is shown in full and that connected with the right-hand key-bar is shown dotted in order to indicate its proper position. The key-bar 84 at the rear has connected to it an arm 86, which stands in a substantially vertical position and is connected at the top with a thrust-rod 87. This rod 87 is slotted at the outer end and adapted to engage with the pin 881, carried by the arm 88. This arm 88 is secured at the left end of the rod 880, which is pivoted in the frame of the machine. Near the longitudinal center of the machine is situated the arm 89, which is carried by the shaft 880. This arm 89 is pivoted to a yoke 90, carrying a shive or roller 91, upon which the auxiliary rail 131 is adapted to rest. When the key-bar 84 is depressed, as shown in Fig. 1, the

arm 86 in moving forward thrusts the rod 87 forward, and thus by engaging the pin 881 shifts the roller 91, and consequently the platen-frames 7 and the platen 2 by means 5 of the auxiliary rail 131. When the pin 722, carried by the plate 7, contacts with the stop 225, carried by the side frame 22, the upper movement of the platen is determined, and the type when operated will strike in the upper-case position. Carried by this key-bar 84, at the left, is a link 96, which is pivoted to the arm 97. This arm 97 is pivoted at 98 and serves to operate the notched plate 99, which is adapted to engage with one end of 15 the pin 881.

When the parts are in their normal position, the pin 881 rests in the lower notch in the plate 99. When the key-bar 84 is depressed, the plate 99 moves and releases the 20 pin 881, so that the arm 87 may move the pin forward, and consequently lift the platen through the medium of the roller 91. Upon release of the key-bar 84 the parts return immediately to their original lower-case position. 25

On the right-hand side of the machine is a construction for operating the shifting device similar to that on the left-hand side, already described. It differs from it in this, 30 however, that there is no locking-plate 99 and operating part. Consequently when the key-bar 85 is depressed the arm 86' moves forward and thrusts the rod 87' so as to engage the pin 881', and thus rotate the shaft 35 880. By this operation, the shaft 880 being rocked, the pin 881, carried by the arm 88, moves correspondingly, so as to raise the platen as before. The pin 881, however, which is in engagement with the notched 40 plate 99, depresses the plate slightly, slips out of the lower notch and into the upper notch, where it is held by the tension of the parts. The platen and other parts will be held in the upper-case position for writing a line of 45 upper-case characters until released by the depression of the left-hand key-bar 84. The release will be clearly understood, but, briefly, is performed by depressing the left-hand key-bar 84, so as to release the plate 99 and permit the pin 881 to become free. The weight 50 of the carriage parts and the platen will then return the construction to the lower-case position. Both of the thrust-rods 87 and 87' have slots in the front ends similar to the 55 slots 870', so that the pins 881 and 881' may be moved independently by the "temporary" or "line" shift-key bars.

The ribbon-guiding mechanism is operated with the platen-shifting mechanism, so as to 60 bring the ribbon into a position suitable for the operation of the type in both case positions. This construction is more completely set forth and claimed in my application, Serial No. 109,925, filed June 2, 1902. It 65 consists, briefly, however, in the lifter-rod 92,

which is attached to the yoke 90 and guided by the stationary arm 93 and the U-shaped lever 94, pivoted to the rod 92 and in its turn pivoted to the ribbon-guiding rod 95 and guided by the arm 32. When the platen is shifted by the movement of the yoke and shive 91, the rod 92 is raised, carrying with it the lever 94, and consequently the ribbon-guide 95. The operation of the universal bar 31 will therefore tilt the lever 94 about 70 its movable axis, guided by the arm 32, whether the parts are in the upper or lower case position. Of course when the platen is locked in the upper-case position the operating center of the lever 94 is correspondingly held in its upper position. 75

The temporary shift-key-bar 84 is the one used for shifting the platen temporarily for single-character printing. The line shift key-bar 85 shifts the platen for printing a line or 80 number of characters in the upper case. 85

The advantages of this construction in permitting the carriage to be shifted for the purpose of operating the type in the upper-case position, either singly or in a series, and of 90 releasing the structure will be obvious. The structure is such that the parts are subject to but little wear and are so positioned in relation to the other parts of the mechanism as not to interfere with the operation of the 95 machine.

What I claim is—

1. In a type-writing machine, a platen-shifting mechanism including an auxiliary guide-rail, a roller coacting therewith, means for raising one of said parts comprising a rock-shaft, an arm carried thereby for connecting with one of said first-mentioned parts, a second and a third arm carried by said shaft one at each end, a horizontally-positioned thrust-rod adapted to engage each of said second and third arms for independently operating the same, two shift-key bars and upright arms from said shift-key bars pivoted to said thrust-bars for the purpose specified. 100

2. In a type-writing machine, the combination of carriage side frames, platen-carrying frames carried thereby, a platen mounted in said latter frames, front and rear guide bars or tracks for said carriage-frames, an auxiliary bar or track for the front of said platen-carrying frames, all of said bars or tracks being located back of the front of the platen, and key-controlled means for lifting said platen from lower to an upper case position, coacting with said auxiliary bar or track. 115

3. In a type-writing machine, a carriage-body having side frames and a platen-carrying frame pivoted thereto, a front and rear guide for said carriage, an auxiliary guide-rail at the front of said platen-frame, a lifting guide-roller for said auxiliary rail said roller having a frame, means for moving said 120

130

frame comprising two shift key-bars, a slotted cross-bar controlled by each key-bar, and a bell-crank lever having three arms, two of the arms of said lever engaging said slotted cross-bars and the other arm of said lever connecting to said roller-frame.

- 5 4. In a type-writer machine, a carriage-body having side frames and a platen-carrying frame pivoted thereto, a front and rear 10 guide for said carriage, an auxiliary guide-rail for said platen-frame, a lifting guide-roller for said auxiliary rail, said roller having a frame, means for moving said frame comprising a shift-key bar, a slotted cross-bar 15 controlled thereby, and a bell-crank lever, one of the arms of said lever engaging said slotted cross-bar and the other arm of said lever connecting to said roller-frame, said roller-frame having a downwardly-projecting 20 slotted arm, a stationary arm carrying a pin to engage in the slot of said slotted arm to guide the movements of said roller.
- 5 5. In a type-writing machine, a carriage-body having side frames and a platen-carrying frame pivoted thereto, a front and rear 25 guide for said carriage, an auxiliary guide-rail at the front of said platen-frame, a lifting guide-roller for said auxiliary rail, said roller having a frame, means for moving said frame 30 comprising a shift-key bar, a slotted cross-bar controlled thereby, and a bell-crank lever, one of the arms of said lever engaging said slotted cross-bar and the other arm of 35 said lever connecting to said roller-frame, said roller-frame having a downwardly-projecting slotted arm, a stationary arm carrying a pin to engage in the slot of said slotted

arm to guide the movements of said roller, the lower end of said slotted arm being pivoted to a lever which in turn has a pivot, and 40 a universal shaft having a slotted lever co-operating with the pivot-pin in said lever to guide the same.

6. In a type-writing machine, a vertically-movable platen, side plates carrying said 45 platen, a main rear guide bar or track extending from side to side of the machine at the rear of said platen, a guide member connected to said plates and located substantially midway between the same, for coacting 50 with said main guide bar or track, a bar connecting the front ends of said plates below said platen and back of the printing position, and key-controlled means for lifting said platen through the medium of said bar or 55 track.

7. In a type-writing machine, carriage side plates, bars connecting the front and rear thereof, guides for said bars, platen side carrying-plates supported by said carriage 60 side plates, an auxiliary bar connecting the front ends of said platen-carrying plates all of said bars being to the rear of the printing position, key-controlled mechanism coöperating through the medium of such auxiliary 65 bar for lifting said platen, and means carried by said carriage side plates and said platen-carrying side plates for mutual co-operation to limit the upward and downward movement of said platen.

JESSE ALEXANDER.
